GYROSCOPE CONTROL

Franz Fischer, Berlin-Wilmersdorf, Germany;
vested in the Attorney General of the United
States

Application November 10, 1939, Serial No. 303,734
In Germany November 10, 1938

3 Claims. (Cl. 74—5)

1

This invention relates to gyroscopes, and more particularly to gyroscopic horizons for vehicles such as aircraft.

Devices have heretofore been proposed of this character wherein a gyroscopic horizon is provided with means which are responsive to gravity for imparting stabilizing forces or moments thereto. Such means, for example, pendulums tend to leave their true vertical position when the craft upon which they are mounted changes course or speed thereby producing longitudinal or transverse accelerations. Pendulums under the action of these disturbing accelerations will assume an apparent instead of a true vertical position. The stabilizing forces which are dependent upon the position of the pendulum will consequently have the effect to move the plane of the gyroscopic horizon into such a position that it is perpendicular to the apparent vertical rather than the true vertical.

One of the objects of the present invention is to provide novel means for maintaining a gyroscopic horizon in a plane perpendicular to the true vertical.

Another object of the invention is to provide novel means for maintaining a gyroscopic horizon in the true horizontal wherein the effect of the longitudinal or transverse accelerations of a vehicle upon which the novel means are mounted are compensated for.

A further object is to provide novel means for stabilizing a gyroscopic horizon, the directive force of which means is effective at all times during the operation of the gyroscopic horizon.

Another object is to provide a gyroscopic horizon which is at all times under the influence of stabilizing means.

The above and further objects and novel features will more fully appear from the detailed description when the same is read in connection with the accompanying drawings. It is to be expressly understood, however, that the drawings are for purposes of illustration only and are not intended as a definition of the limits of the invention, reference for this latter purpose being had to the appended claims.

In the drawings, wherein like reference characters refer to like parts throughout the several views,

Fig. 1 is an isometric view partly in section and partly diagrammatic of one embodiment of the invention;

Fig. 2 is an isometric view partly in section of acceleration compensating means employed with a second embodiment of the invention; and

2

Fig. 3 is an isometric view of a gravity responsive stabilizing device which may be employed with the embodiment of Fig. 2.

The forms of the invention illustrated in the accompanying drawings, by way of example, comprise a conventional gyroscopic horizon apparatus having stabilizing means which are constituted by means for exerting a turning moment at a suitable point upon the gyro horizon, the last named means being a gravity responsive device, for example, a pendulum which governs the stabilizing force producing means in accordance with departures of the gyro horizon from a predetermined relationship with the gravity responsive device. Novel means are provided for stabilizing the gravity responsive device and for compensating for the effect of disturbing accelerations thereupon comprising means for measuring accelerations which arise in a direction of oscillation of the gravity responsive device. The latter, under the action of the stabilizing forces, consequently remains in the direction of the true vertical and thus maintains the horizon in the true horizontal plane.

In the form shown in Fig. 1 the gyroscopic horizon is constituted by a conventional rotor 10 which is rotatable on trunnions 11 which are mounted for rotation upon an inner gimbal ring 12, the latter being provided with trunnions 13. The latter trunnions are conventionally mounted upon an outer gimbal ring or frame 14 which is mounted by means of trunnions 15 upon fixed bearings 16, upon a vehicle such as aircraft. The trunnions 15 are parallel to the transverse axis of the craft, the direction of advance of the craft being indicated by arrow 17.

The center of gravity of the gyro rotor preferably coincides with the point of intersection of the axes of trunnions 13 and 15.

Suitable stabilizing moment producing means which act directly upon the mounting of the gyroscope, and which are controlled by means which are later to be explained, comprise a rotary magnet 18 which includes an armature 19 which is rigidly connected to an extension of the trunnion 13, and a stator 20 which is rigidly mounted upon the outer gimbal ring 14. Armature 19 is provided with two exciter windings which are wound in opposite directions and which are connected by means of leads 21 and 22 with the extremities of a resistance 23, the leads 21 and 22 each being connected to an extremity of one of the above mentioned oppositely wound exciter windings. A sliding contact 23a is connected by means of a lead 24 through a

power source 25 to a common tapping point of the above mentioned exciter windings.

Resistance 23 and sliding contact 23a comprise parts of the above mentioned gravity responsive device, the remainder of which is constituted by a mounting member 26 for the resistance 23, the member being preferably rigidly connected to one of the trunnions 15. Sliding contact 23a is rigidly attached to a pendulum 21 which is attached to and mounted for movement with a shaft 28, the latter resting in a fixed bearing 29.

In operation of the apparatus so far described both the windings of the armature 19 are energized equally in the zero or central position of the sliding contact 23a as shown in Fig. 1. Consequently the oppositely acting turning moments acting on a trunnion 13 compensate one another and no stabilizing force is communicated to the gyro. However, if the plane of rotation of the rotor 10 angularly deviates from the horizontal about the axes of trunnions 15, the deviation being due, for example, to bearing friction, the mounting member 26 and therewith the resistance 23 will angularly shift, thereby moving the sliding resistance 23a away from its central position upon the resistance. The rotary magnet 18 will exert a turning moment upon the trunnion 13 which corresponds in magnitude and direction to the movement of the resistance 23 and sliding member 23a from the initial position, thereby causing the gyro to precess about the outer gimbal trunnions until the mounting member 26 and therewith the resistance 23 are restored to their initial centralized position. Thus the axis of rotation of the rotor will tend to seek a position which is parallel to the longitudinal axis of the pendulum, i. e., the apparent vertical.

Novel means are provided for maintaining the pendulum in the true vertical comprising apparatus for measuring, in the embodiment shown, accelerations in the direction of advance, and for exerting a compensating moment upon the pendulum in response to the measured acceleration. The means are constituted by a rotary magnet 30 having an armature 31 which is preferably rigidly attached to shaft 28 upon which the pendulum is mounted. The armature 31 is provided with a double winding analogous to the one previously mentioned in connection with rotary magnet 18.

The rotary magnet 30 is operatively connected, in a manner to later appear, with acceleration measuring means comprising a propeller 32 which is rotatable by the relative or head wind and which, by means of a shaft 33 which is provided with slip rings 34, rotates a housing member 35 which is preferably cylindrical. Rotatably mounted within the housing 35 is a shaft 36 upon which is attached a fly wheel 37. Resilient means are provided causing the shaft 36 to rotate with the housing 35 comprising a spring member 38 which is preferably coiled about the shaft, and in a rest position is in the shape of a spiral of Archimedes or a logarithmic curve, as shown in Fig. 1, with the inner extremity of the spring attached to the shaft and the outer extremity of the spring attached to the housing. Suitable means for damping relative movements of the shaft 36 and member 35 are provided comprising an eddy current damper including, for example, a cylinder 39 upon shaft 36, the cylinder being rotatable within a magnet 40.

The operative interconnection of rotary magnet 30 and the acceleration responsive means comprises a potentiometer device 41 which is con-

stituted by a resistance 42 which, in the form shown, is semi-circular in shape and in contact with a sliding finger 43, the latter being rigidly connected to shaft 36, and the resistance being mounted upon the member 35. The finger 43, by means of the spring 38, lead 44, one of the slip-rings 34, and a lead 45, is connected to the armature 31. The opposite extremities of the resistance 42, by means of suitable leads, are connected to two of the slip-rings 34 and, by means of leads 46 and 47, are connected to the positive and negative terminals of a source of electric energy. Interconnecting these positive and negative terminals is a resistance 48 to the center of which is connected a lead 49, the latter being also connected to armature 31.

In operation the angular speed of shaft 33 is proportional to the relative or head wind and therefore to the air speed of the plane. At a constant air speed of a plane, i. e., at a constant speed of the propeller 32, the housing 35 and the fly wheel 37 are in synchronous rotation and the potentiometer apparatus 41 is in a centralized position as shown in the drawing. However, if due to an acceleration or deceleration the speed of the propeller 32 changes, then the housing 35 is accelerated or decelerated therewith. Fly wheel 37, due to inertia, continues to rotate temporarily at its previous angular speed and the finger 43 of the potentiometer is deflected from the central position in response to the acceleration or deceleration. As a result of the coupling by means of the spring 38, the fly wheel 37 and therewith finger 43 are brought to the new speed of rotation of the housing 35 and finger 43 is recentered.

As long as there exists between the two rotatable members 35 and 37 a relative displacement which is correct in direction, and at least approximately correct in magnitude, to the flight acceleration or deceleration, then a corresponding relative displacement occurs between the finger 43 and resistance 42 of the potentiometer. The movement of finger 43 from its central position will cause the rotary magnet 30 to produce a moment which will compensate or balance the disturbing moment created by the acceleration or deceleration of the craft. If the angular speed of the flywheel 37 becomes equal to that of housing 35, then the finger 43 returns to a central position and the rotary magnet 30 no longer receives electric impulses.

A second embodiment of a measuring device for acceleration is shown in Fig. 2 wherein a propeller (not shown) is operatively connected by means of shaft 50 to a cylindrical member 51 having rotatably mounted therein an inner shaft 52 upon which is mounted a flywheel 53. There is also mounted upon shaft 52 an armature 54 of a tachometer generator. Suitable magnet poles 55 are mounted in a conventional manner adjacent the armature and rigidly attached to the housing or cylindrical member 51 and adapted for rotation therewith. Also mounted upon housing 51 are diametrically opposed brushes 56 which are in contact with a conventional commutator 57. The diametrically opposed brushes are electrically connected by means of leads 58 and slip-rings 59, there being one lead and one slip-ring for each brush, to a rotary magnet which can, for example, be similar to the rotary magnet 30 of Fig. 1.

In the embodiment shown in Fig. 1, a mechanical coupling was described for the housing 35 and the shaft 36. However, in the present em-

bodiment no mechanical coupling is employed. Consequently, in operation there occurs in the event of an acceleration of the housing 51 relative to the shaft 52 an electromagnet braking action between the armature 54 and the advancing or lagging poles 55. The poles in this manner exert a torque upon the armature which tends to synchronize the speed of said armature and housing 51. The current which is created during the relative rotation of the parts of the generator comprises a measure of the angular acceleration of the propeller and is conducted by the commutator, the brushes and connected conductors to the above mentioned rotary magnet.

A modification of the arrangement of the pendulum device and the interconnected rotary magnet above described is illustrated in Fig. 3, which is similar to the above mentioned pendulum device with the exception that a resistance 60, which is analogous to the resistance 23, is rigidly mounted upon the aircraft proper rather than mounted upon a trunnion such as 15 (Fig. 1).

There is thus provided novel means for maintaining the rotor of a gyroscopic horizon in a correct and true horizontal position, the means being simple in construction and light in weight. Furthermore, the novel means are extremely sensitive but are not easily moved out of adjustment. The parts for the acceleration measuring apparatus are well shielded and only such forces act upon the rotating parts thereof which are responsive to the speed and acceleration of the craft.

Although two embodiments of the present invention have been illustrated and described in detail, it is to be expressly understood that the invention is not limited thereto. For example, instead of employing a propeller to rotate one of the members of the acceleration measuring devices, it is possible to operatively interconnect one of said members directly to the engine of the aircraft. Also it would be possible to control, e. g., shaft 33 by means of a conventional type of speedometer in such a manner that the speed of said shaft is a function of the speed of the aircraft. Various changes may be made in the design and arrangement of the parts without departing from the spirit and scope of the invention as the same will now be understood by those skilled in the art. For a definition of the limits of the invention, reference will be had primarily to the appended claims.

What is claimed is:

1. The combination with a gyro rotor in a gimbal ring suspension of means for exerting a stabilizing force thereupon, true vertical defining means, means for governing the first named means in response to movements of the plane of the rotor relative to the true vertical defining

means, means actuatable by electricity for exerting a stabilizing moment upon the true vertical defining means, a generator including an armature and pole shoes, a flywheel drivably connected to the armature, a propeller drivably connected to the pole shoes, and means for electrically connecting the generator and said means actuatable by electricity.

2. The combination with a gyro horizon including a gimbal ring suspension, the horizon being mounted upon a vehicle, of means for exerting a force upon the suspension, means responsive to movements of the gyro from the true vertical for controlling the first named means to return the gyro to said true vertical, a flywheel member, a rotatable member, a propeller operatively connected to the rotatable member, means for resiliently interconnecting the flywheel and rotatable member, and means for exerting a force upon the second named means in response to changes from a predetermined angular relation of said members, whereby said gyro is prevented from assuming an apparent vertical position during acceleration and deceleration of the vehicle.
3. In apparatus of the class described, a gyro rotor mounted in a gimbal ring suspension adapted to be carried on an aircraft, means for exerting a turning moment upon the suspension, gravity responsive means for governing the first-named means, means for exerting a turning moment upon the gravity responsive means, a member rotatable at a speed proportional to the velocity of flight, a fly wheel resiliently interconnected to said member, and means for controlling the moment exerted upon said gravity responsive means in response to changes in angular relationship between the member and fly wheel to prevent said gravity responsive means from establishing an apparent vertical.
